UNITED STATES PATENT OFFICE

JAMES E. WYSONG, OF RICHMOND, VIRGINIA, ASSIGNOR TO LARUS & BROTHER COMPANY, OF RICHMOND, VIRGINIA, A CORPORATION OF VIRGINIA

PACKAGE CONVEYING, CLOSING, AND SEALING MACHINE

Application filed June 15, 1928. Serial No. 285,729.

My invention relates to a machine for conveying a paper or cardboard carton or the like, having means for applying an adhesive to the ends of the same, and for closing the carton and passing it along with the closed ends held under tension in their closed position for a predetermined length of time, and for re-conveying the sealed cartons in close proximity to the place from whence they were 10 originally conveyed.

It is an object of the invention to provide a simplified and improved construction of this character which will accurately and satisfactorily perform the function for which 15 it is designed, all as will be more particularly hereinafter set out and claimed.

Referring to the accompanying drawings which are made a part hereof and on which similar reference characters indicate similar 20 parts,

Figure 1 is a perspective illustrating one application of my invention,

Figure 2, a side elevation,

Figure 3, a top plan view,

25 Figure 4, is a section on line 4—4 of Figure 3,

Figure 5, a section on line 5—5 of Figure 3,

Figure 6, a section on line 6—6 of Figure 3,

Figure 7, a fragmentary side elevation of the discharge end of the machine, and

Fig. 8, a top plan view of such discharge end.

35 In the drawings reference character 10 indicates supporting legs upon which is mounted an upper runway or trough 11 for a conveyor belt 12, said runway comprising side bars or members 13 and 14, and bottom member

40 11. The conveyor belt 12 is formed of flexible fabric and is provided on its upper surface with transverse cleats or cross members 12' formed of leather or other desired material adapted to engage paper cartons or

45 boxes C placed thereon by hand, for carrying them through the machine. The paper cartons or boxes are open at each end and have four flaps, a, b, c and d, one at each side, one pair of opposed flaps, c and d folding inside, and the other pair of opposed

flaps, a and b disposed at right angles being adapted to be supplied with paste or adhesive material, and to be folded over the other flaps c and d and pressed against the ends of the carton for properly sealing the same and rendering the carton substantially air tight. The carton is placed upon the conveyor with the inner flaps c and d folded in and disposed in vertical position, while the outer flaps a and b or extensions of the upper and lower horizontal surfaces, are disposed in any position between the vertical and the horizontal.

Means is provided for folding down or opening the flaps which form the extensions of the lower horizontal surface in order that they may when in horizontal position receive adhesive material from a pair of primary mucilage troughs, and such means comprises a nose or projection 16 which tapers at 17 from its outer to its inner side and presents a thin point or blade which projects slightly over the conveyor belt in the runway in a position to engage behind the bottom flap of the carton. The nose 16 is provided with a tail piece 18, which extends downwardly and rearwardly into close proximity to the upper surface of the side bar 13 in order to bend and guide the flap a downwardly into horizontal position, such tail piece being curved at its forward edge as shown at 19, so that it will operate gradually upon the flap and prevent mutilating the same. The nose 16 is supported by means of a curved supporting strap 20, which has its outer end secured to a base member 21 adjustably mounted upon the outwardly extending horizontal flange 22 of a bracket having a depending flange 23 secured to the exterior of the side bar.

A pair of similar brackets 24 are mounted in the same relative positions as the brackets just described, in slightly spaced relation in advance of the same, and upon each is adjustably supported a mucilage trough 25 which is spaced slightly above the upper surface of the side bar and is provided with a mucilage roller 26 having peripheral contact with a second mucilage roller 27 adapted to engage the inner side of the bottom flap a of the carton and apply mucilage thereto.

The mucilage trough 25 is supplied from a cylindrical reservoir 28 mounted upon an upstanding arm or bracket 29 fixed to the side bar, said cylindrical reservoir having an opening (not shown) in its top through which the mucilage may be supplied and having a control valve 30 in its bottom connected by means of a rubber tube 31 to a funnel 32 which communicates with the mucilage trough. The mucilage trough is also provided with a drainage or discharge pipe 33. The roller in the mucilage trough is mounted upon a shaft 34, and said shaft is provided with a pair of gears 35 and 36, the outer gear 35 serving to drive the shaft from a gear 37 mounted on a shaft 38 which extends across the machine and is supported by the brackets 29, the inner gear 36 serving to drive a gear 39 mounted upon a shaft 40 which supports the mucilage applying roller 27. The shaft 38, upon which the gears at each side of the machine are mounted, serves to drive the mucilage supplying rollers simultaneously and such shaft is driven by means of a sprocket 41 adjustably mounted on the shaft adjacent one end of the same, from the sprocket chain 42.

The bracket 29 at the side of the machine at which the sprocket chain 42 is mounted is provided with a brace 43 which serves to maintain the same in fixed relation against the pull of the sprocket chain. In order to maintain the sprocket chain under proper tension an idler 44 is adjustably mounted on said brace 43.

A carton placed upon the conveyor at the right, Figures 2 and 3, will be carried through the above described part of the machine, and have its lower flaps *a* properly moistened with mucilage. The tapering nose 17 slips in behind the flap and as the carton is moved along, such nose folds the flap downward so that it will travel beneath the tail piece 16 and the mucilage roller. Means is next provided for closing the bottom flaps *a*, for opening the top flaps *b*, and for applying mucilage thereto, and for closing such top flaps.

In advance of the mechanism described for applying mucilage to the lower flaps are disposed a pair of closing straps 45 mounted in opposed relation, one at each side of the machine on top of the side bar. Each closing strap comprises a supporting foot fixed to its respective side bar and a portion inclined at an angle of substantially 45 degrees, and with a horizontal upper portion or extremity disposed in parallel relation to its foot, the inner edge 46 of the inclined portion being tapered from said foot inwardly over the conveyor to its upper horizontal portion to effect a gradual closing of the lower flap, such lower flap being carried with its forward edge extending outwardly in position to engage the inclined portion of the strap and be gradually

turned up into closed position by the tapered inner edge. At the same time the upper flap will engage the inclined portion of closing strap 45 and be elevated to horizontal position and will pass between the free upper ends of the closing straps and the spaced guides 47. Beneath the horizontal portions of the closing straps are mounted an additional or secondary pair of mucilage troughs 48 adapted to supply mucilage to the upper flap *b* at each end of the carton, each trough being provided with a transverse shaft 49 upon which is fixed a mucilage roller 50 which is in position to directly engage the under side of the upper flap *b* of the carton as it passes thereover. The transverse shafts 49 are mounted in alignment similar to the transverse shafts upon which the primary mucilage rollers are disposed. The upper flap is held in contact with the mucilage roller 50 by means of an opposed thinner co-acting roller 51 fixed upon a shaft 52. The roller 51 has a peripheral flange or bead at each side which flanges form a groove therebetween, and by means of which sufficient pressure is exerted upon the flap to cause the application of the mucilage, but when the flap is not between the rollers 50 and 51 the narrow roller 50 will not engage the roller 51 and apply mucilage thereto. The shaft 52 is supported in bearings 53 adjustably fastened by means of bolts 54 upon brackets 55, said bolts extending through vertical slots 56 in said brackets. The last mentioned shaft 52 is provided with a pulley 57, which is driven by means of a belt 58 from a source of power (not shown). The shaft 52 is provided with a gear 59 adjacent each end, which engages a gear 60 on the shaft 49 for driving the mucilage roller 50. The shaft 52 is also provided with a sprocket 61 about which the sprocket chain 42 extends for receiving power for driving the primary mechanism for supplying mucilage to the lower flaps. Each secondary mucilage trough is supplied from a cylindrical reservoir 28 through the control valve 30 and rubber tube 31, such cylindrical reservoir being supported upon an arm 28' mounted upon the bracket 55.

It will be understood from the foregoing that the upper flaps *b* having just been supplied with mucilage on their inner surfaces are ready to be closed down over the lower flaps *a* to complete the closing of the carton. In order to perform this operation I provide a pair of inclined closing straps 62 which are formed integrally with, and therefore support the guides 47 which are extensions of the horizontal upper portions of the closing straps. Each closing strap tapers downwardly from its horizontal upper portion substantially at an angle of 45 degrees to its supporting foot disposed parallel to its upper portion, in off-set relation thereto, or in a substantially horizontal posi-

tion fixed upon the side bar of the machine. The inner edge 63 of the inclined portion of the closing strap tapers from its upper end downwardly and inwardly slightly over the conveyor in order to effect a gradual closing of the flap. Additional means is provided for pressing the upper flaps to insure a complete sealing, such means comprising a roller 64 having a flange 65 at each end, which engages the end of the carton. The roller 64 is mounted upon a shaft 66 supported in bearings 67 mounted upon brackets 68, said brackets being secured in position by bolts or other fastening means which also 15 secure the closing straps in position. The roller shaft 66 is provided with a sprocket 70 which is driven by a sprocket chain 71 extending around a sprocket 72 on the shaft 52. An idler 44 is mounted upon a bracket 73 for maintaining the proper tension on the 20 chain.

I have previously described mechanism for opening out respectively the lower and upper horizontal flaps at opposite ends of 25 a carton or container and for applying adhesive to the inner surfaces of such flaps and for closing the flaps. In order to hold the flaps closed a sufficient time to permit the adhesive to dry or set, I provide a pair of side 30 conveyors 74 which operate in timed relation with the horizontal conveyor 12, and I provide means for yieldingly maintaining the inner run of the side conveyors in engagement with the ends of the carton. Below 35 the upper runway 11 is mounted a lower runway 75 in which operates a return conveyor belt 76 for returning the sealed cartons in close proximity to the point whence they started, the cartons being deposited on the 40 lower conveyor belt by a dumping mechanism hereinafter more particularly described. The side conveyors are mounted upon pulleys 77 supported by vertical shafts 78 mounted in brackets 79 attached to the sides of the 45 upper and lower runways, a smaller pulley 80 being employed for maintaining the inner run of the side belts or conveyors in a pre-determined position, said smaller pulleys being mounted upon vertical shafts 81 slightly 50 spaced from the periphery of the pulleys 77 and having their upper ends held in proper spaced relation by a strap 82 and braced against the pulling action of the belt by a pair of brackets or braces 83. Against the rear 55 side of the inner run of each belt 74 is disposed a backing plate 84 resiliently held in engagement with the belt by means of springs 85 mounted upon horizontal studs 86 which extend through transverse slots in upright 60 brackets 87, a nut 88 being provided for varying the tension on the spring 85. The brackets 87 are merely rods or bolts supported in upright or perpendicular position upon the side bars of the machine and having 65 apertures therethrough at right angles to

their axes. With this construction the inner surfaces of the belts will be caused to press firmly but resiliently against the ends of the cartons as they are carried along.

The upper and lower conveyor belts 12 and 76 are mounted upon pulleys 89 and 89', the upper belt 12 terminating at the discharge end of the side conveyors while the return conveyor projects slightly beyond said side conveyors. I extend the side bars 13 and 14 slightly beyond the conveyor 12 and between the extremities of the side bars I pivot a dumping board 90, which is mounted upon a shaft 91 supported in bearings 92 on the under side of the side bars. An arm 93 is fixed on the extremity of the shaft 91, and a spring 94 fastened to one of the side bars for maintaining the arm in a position approximating the horizontal, with the dumping board 90 forming a continuation of the horizontal upper conveyor. Said dumping board is normally held in horizontal position under the action of the spring, but the spring is too weak to support the weight of the filled carton, and will permit the same to drop downwardly onto the return conveyor while the dumping board will, under the action of the spring, be returned to its normal horizontal position. The dumping board is mounted eccentrically of its supporting shaft, and the short end of the board which is not engaged by the packages engages a pair of pads or cushions 95 mounted upon a cross bar 96 which is fastened to the side bars 13 and 14. In discharging from the conveyor 12 the carton will be given a quarter turn and when carried along by the belt 76 and discharged for packing, it will be given another quarter turn so that it is in the proper position for packing.

Power for operating the conveyors may be supplied from any desired source. I have shown a relatively large pulley 97 mounted on the shaft 98 upon which the conveyor belt pulley 89' is mounted. The shaft 98 is provided with a bevel gear 99 which drives an upright shaft 101 by means of a similar gear 100. The upright shaft 101 carries a similar bevel gear 102 on its lower extremity, which is engaged by bevel gear 103 on a horizontal shaft 104 and which drives by means of bevel gears 105 and 106 the pulley 89', and which drives by means of pulleys 107 and 108 the vertical shaft upon which the pulley 77 is mounted. The upright pulley shafts 78 are driven in synchronism by any desired means, for example, a cross shaft 109 having bevel gears on each end which mesh or engage gears on the vertical pulley shaft 78.

It will be obvious to those skilled in the art that various changes may be made in my device without departing from the spirit of the invention, and I, therefore, do not limit myself to what is shown in the drawings and

described in the specification, but only as set forth in the appended claims.

Having thus fully described my said invention, what I claim as new and desire to secure by Letters Patent, is:

1. A device of the class described, comprising a conveyor adapted to receive cartons to be closed and sealed, a member projecting over the side of the conveyor in a position to engage and open the lower flap, a mucilage roller for applying adhesive to the inner surface of the flap, an inclined tapered strap for closing the lower flap and for guiding the upper flap to open position, a mucilage roller for applying adhesive to the inner surface of the upper flap, a co-operating roller having peripheral flanges at each side for engaging the flap and holding it in engagement with the mucilage roller, an inclined tapered strap for closing the upper flap, and means as the carton is carried along for yieldingly holding the flap closed to permit the adhesive to set, substantially as set forth.

2. A device of the class described, comprising a conveyor adapted to receive cartons to be closed and sealed, a member projecting over the side of the conveyor in a position to engage and open the lower flap, a mucilage roller for applying adhesive to the inner surface of the flap, an inclined tapered strap for closing the lower flap and for guiding the upper flap to open position, a mucilage roller for applying adhesive to the inner surface of the upper flap, a co-operating roller having peripheral flanges at each side for engaging the flap and holding it in engagement with the mucilage roller, and means for closing the upper flap as the carton is carried along, substantially as set forth.

3. A device of the class described comprising an upper and lower runway, a conveyor belt in each runway, side members for each of the runways extending above the conveyor belt, means projecting inwardly over the conveyor belt at each side for bending open the lower flaps of a paper carton, a mucilage roller for supplying adhesive to the inner surface of said flaps while in their bent open position, an upwardly inclined strap at each side of the conveyor, having its inner edge tapering inwardly over the conveyor, for closing the lower flaps and for opening and guiding the upper flaps, a mucilage roller mounted adjacent each closing strap in a position to be engaged by an upper flap, a co-operating roller in spaced relation to the mucilage roller having peripheral flanges terminating in the plane of the peripheral surface of the mucilage roller whereby mucilage will be prevented from getting on the co-operating roller when the flap passes from between the rollers, a downwardly extending inwardly tapering strap for closing the upper flap, and means at each side of the conveyor operating in synchronism therewith as the

carton is carried along for yieldingly holding the flaps closed to permit the adhesive to set, substantially as set forth.

4. A device of the class described comprising an upper and lower runway, a conveyor belt in each runway, side members for each of the runways extending above the conveyor belt, means projecting inwardly over the conveyor belt at each side for bending open the lower flaps of a paper carton, a mucilage roller for supplying adhesive to the inner surface of said flaps while in their bent open position, an upwardly inclined strap at each side of the conveyor, having its inner edge tapering inwardly over the conveyor, for closing the lower flaps and for opening and guiding the upper flaps, a mucilage roller mounted adjacent each closing strap in a position to be engaged by an upper flap, a cooperating roller in spaced relation to the mucilage roller having peripheral flanges terminating in the plane of the peripheral surface of the mucilage roller whereby mucilage will be prevented from getting on the cooperating roller when the flap passes from between the rollers, and means for closing the upper flap, substantially as set forth. 70 75 80 85 90

5. A device of the class described comprising a runway, a conveyor belt in said runway, means projecting inwardly over the conveyor belt for bending open the lower flaps of a paper carton, a mucilage roller for supplying adhesive to the inner surface of said flaps, an upwardly inclined strap at each side of the conveyor, for closing the lower flaps and for opening and guiding the upper flaps, a mucilage roller mounted adjacent each closing strap in a position to be engaged by an upper flap, and a co-operating roller in spaced relation to the mucilage roller having peripheral flanges terminating in the plane of the peripheral surface of the mucilage roller whereby mucilage will be prevented from getting on the cooperating roller when the flap passes from between the rollers, substantially as set forth. 100 105 110

6. A machine for conveying cardboard cartons and for closing and sealing the ends of said cartons, comprising a runway having a horizontal bottom, side members extending above the bottom, a conveyor belt in said runway, cleats on said belt for engaging and propelling the cartons, primary mucilage applying mechanism for moistening lower flaps of the cartons comprising a mucilage trough 115 mounted at the side of the conveyor and a mucilage roller spaced slightly above the side member and adapted to be supplied with mucilage from the trough, a bracket at the side of the conveyor, a lower flap engaging projection adjustably carried by the bracket and extending over the conveyor belt in a position to engage the inside of the lower flap of the carton and guide the same to open position and downwardly beneath the mucilage 120 125 130

- roller, secondary mucilage applying mechanism for moistening the upper flaps of the cartons comprising a mucilage trough mounted at the side of the conveyor, a mucilage applying roller in the mucilage trough, means for guiding the upper flaps of the cartons to open position and over the mucilage roller, said means also serving to close the lower flaps and a roller disposed above the mucilage roller and having a peripheral flange at each side disposed in the plane of the peripheral surface of the mucilage roller, for pressing said flaps against the mucilage roller, substantially as set forth.
7. In a carton sealing machine, a conveyor for the cartons, means for opening the lower flap, means for applying adhesive to the inner surface of the lower flap, an inclined tapered member for closing the lower flap and for moving the upper flap to adhesive receiving position, substantially as set forth.

In witness whereof, I have hereunto set my hand at Richmond, Virginia, this 1st day of June, A. D. nineteen hundred and twenty-eight.

JAMES R. WYSONG.
